GARMENT HANGER

Julius Weiss, Arlington, Mass.

Application December 15, 1949, Serial No. 6,633

Term of patent 3½ years

(Cl. D33—8)

To all whom it may concern:

Be it known that I, Julius Weiss, a citizen of the United States, residing at Arlington, in the county of Middlesex, and State of Massachusetts, have invented a new, original, and ornamental Design for a Garment Hanger, of which the following is a specification, reference being had to the accompanying drawing, forming part thereof.

In the drawing:

Fig. 1 is a front perspective view of a garment hanger, showing my new design; and

Fig. 2 is a side elevational view of the same.

The rear of the garment hanger is plain and unornamented.

I claim:

The ornamental design for a garment hanger, as shown and described.

JULIUS WEISS.
